UNITED STATES PATENT OFFICE.

EDMUND J. H. THIEMER, OF NEW YORK, N. Y.

BORING-TOOL.

1,251,133.

Specification of Letters Patent.

Patented Dec. 25, 1917.

Application filed December 16, 1916. Serial No. 137,297.

To all whom it may concern:

Be it known that I, EDMUND J. H. THIEMER, a citizen of the United States, residing in the city of New York, borough 5 of Brooklyn, in the county of Kings and State of New York, have invented a certain new and useful Improvement in Boring-Tools, of which the following is a specification.

10 The invention relates to portable wood-boring implements of the angle-boring type, and the object of the invention is to provide a simple easily operated tool adapted for service in floor pockets and other situations difficult of access, in which angle braces of the usual character cannot be employed successfully.

15 The invention consists in certain novel features of construction, and arrangement 20 of parts by which the above objects are attained, to be hereinafter described and claimed.

25 The accompanying drawings form a part of this specification and show an approved form of the invention.

30 Fig. 1 is a side elevation of the improved tool, arranged for boring a vertical hole from below, and partly in vertical section.

Fig. 2 is a transverse section taken on the line 2—2 in Fig. 1, partly in elevation.

Fig. 3 is an elevation corresponding to Fig. 1 but on a smaller scale, showing the tool arranged for boring a vertical hole between the walls of a partition from the 35 enclosed space beneath the floor. The latter and the partition are shown in vertical section.

Fig. 4 is an elevation of the tool alone, 40 corresponding to Fig. 3, seen from the left in that figure. The dotted radial lines show various angular positions in which the boring bit may be set and operated.

Similar letters of reference indicate the 45 same parts in all the figures.

The frame of the tool comprises two main portions at a right angle each to the other; one portion which will be termed the standard, and which extends vertically when the 50 tool is in operation, is a tube A brazed or otherwise firmly secured to an open head A¹ at the upper end and to a somewhat similar open head A² at the lower end. The tube A incloses a driving-shaft B carrying a bevelled gearwheel B² at its lower end within the head A² and a similar wheel B¹ at the

upper end within the head A¹; the driving-shaft B extends across the head A¹ and has a bearing at A³. Above the head A¹ is a handle A⁴ by which the tool may be held and 60 applied.

On one side of the head A¹ is a boss A⁵ serving as a bearing for a laterally positioned short crank-shaft C carrying on its inner end a bevelled gearwheel C¹ in mesh 65 with the bevelled gearwheel B¹, and on its outer end a crank C² by which it may be turned and rotary motion imparted to the vertical driving-shaft B.

From the lower head A² extends a lateral 70 tube D forming the other main portion of the frame, which will be termed the branch.

It receives a tubular extension D¹ forming part thereof, arranged to slide telescopically therein and which may also be rotated 75 relatively thereto as will be described.

The movable tube or extension D¹ carries at its outer end an open head D² and incloses a horizontal driven-shaft E on which is mounted a bevelled gearwheel E¹ in mesh 80 with a similar wheel F¹ supported on a short vertical bit-shaft F mounted in the head D² and is equipped with a chuck or socket-piece, indicated at F² in which is received the shank of a boring bit G firmly held by a 85 screw F³ or otherwise.

The opposite or inner end of the driven-shaft E is splined as at e and extends across and through the opposite wall of the head A² in which it is free to slide, and carries a 90 bevelled gearwheel E² having a feather E³ engaged slidably in the spline e so that this end of the driven-shaft E may slide through the wheel E² while the latter is held in mesh with the bevelled gearwheel 95 B². An extension E³ of the hub of the wheel E² is screw-threaded and receives a collar E⁴ forming with the hub an annular groove by which the wheel is held against movement axially of the shaft E while permitting it to rotate with the latter.

By sliding the tubular extension D¹ into or out of the tube D the distance between the driving-shaft B and bit G may be varied as required in adapting the tool to various 105 situations, and by rotating the extension relatively to the branch D the bit may be projected in any angular direction desired radially of the shaft E. Any suitable means may be employed to hold the branch D and 110 extension D¹ in such relative positions; the means shown comprises a spring dog H

mounted on the outer tube or branch D and projecting inwardly through a hole d in such tube and matching to and received in any one of a series of holes d^1 in the extension D¹. The holes d^1 are preferably arranged as shown in a plurality of circumferential groups so that the bit may be adjusted at any desired distance from the driving-shaft B, within the range of the tool, 10 and also set at any desired radial angle at the distance thus selected.

The tool is designed more especially for service in electric wiring operations, in which it is often necessary to make openings 15 through plates and beams and other obstructions to which access is difficult or impracticable except by great labor or by considerable damage to adjacent walls, floors or ceilings. One such situation frequently encountered is indicated in Fig. 3, in which it is required to bore a hole from the space between adjacent floor joists, through the floor and partition-plate, to the interior of 20 a vertical partition. The improved tool permits this to be easily accomplished with but little, easily repaired, damage, by simply removing a small section of the flooring, one short length of the flooring-board is usually sufficient, cut at a short distance from the 25 subbase, and inserting the tool into the pocket thus formed, having previously adjusted the telescopic branch to provide the required length. The tool is then firmly grasped by the handle and drawn upward to 30 hold the bit to its work, and by turning the crank the bit is rotated to bore the desired hole. After the wiring has been completed the small opening in the floor may be easily and neatly closed.

40 It will be understood that the sizes and proportions of the parts, the character of the frame, the location of the handle A² and crank C², and the means for adjusting the length of the tool laterally, may be varied 45 as found necessary or desirable in adapting the invention to the conditions of service required.

I claim:—

1. In a portable boring tool, a tubular 50 standard with a head at one end with handle,

a head at the other end and a lateral tube extending from the last-named head, a tubular extension on said lateral tube, a driving shaft in the first-named tube, a driven shaft in the last-named tube, gearing and operating means for rotating said shafts, a head on the outer end of said extension, a chuck in said head, gearing intermediate said chuck and driven shaft, and means permitting of longitudinal extension of the driven shaft and its tube and extension. 55

2. In a portable boring tool, a tubular standard with a head at one end with handle, a head at the other end and a lateral tube extending from the last-named head, a tubular extension on said lateral tube, a driving shaft in the first-named tube, a driven shaft in the last-named tube, gearing and operating means for rotating said shafts, a head on the outer end of said extension, a chuck 60 in said head, gearing intermediate said chuck and driven shaft, means permitting of longitudinal extension of the driven shaft and its tube and extension, and spring means carried by the lateral tube for engaging said 65 extension for holding it in its adjusted positions.

3. In a portable boring tool, a tubular standard with a head at one end with handle, a head at the other end and a lateral tube 80 extending from the last-named head, a tubular extension on said lateral tube, a driving shaft in the first-named tube, a driven shaft in the last-named tube, gearing and operating means for rotating said shafts, a head 85 on the outer end of said extension, a chuck in said head, gearing intermediate said chuck and driven shaft, means permitting of longitudinal extension of the driven shaft and its tube and extension, and spring means 90 carried by the lateral tube for engaging said extension for holding it in its adjusted positions, said driven shaft being slidable through its gear and means preventing movement of said gear lengthwise of its 95 shaft.

In testimony that I claim the invention above set forth I affix my signature.

EDMUND J. H. THIEMER.
